UNITED STATES PATENT OFFICE

WILLIAM F. KIESEL, JR., OF ALTOONA, PENNSYLVANIA

BOILER

Application filed June 30, 1927. Serial No. 202,521.

This invention relates to boilers and more particularly to boilers of the locomotive type.

It is the general object of the present invention to provide a novel and improved composite locomotive type boiler making use of the conventional barrel containing fire tubes and adding thereto a plurality of water tubes arranged to form the fire box.

10 The novel features and objects of the invention may be briefly enumerated as follows:

1. The arrangement of a fire tube boiler and a water tube fire box together with a 15 steam drum extending over both the fire box and the boiler and having steam connections with both parts.

2. The use of a one piece foundation ring or mud ring which forms the sole support 20 for the rear end of the boiler.

3. The use of a pair of water drums disposed above and parallel to the upper surface of the mud ring whereby the connecting water tubes are all of the same length 25 throughout.

4. The arrangement of walls of water tubes connecting the mud ring and the water drums in such a manner as to provide a narrow closed fire box with flame passages on 30 the outside thereof so that the fire box tubes are exposed to the flames on both sides.

5. The arrangement of a water tube fire box entirely closed off from the combustion space at the front end in such a manner that 35 the flames must first pass rearwardly and then reverse themselves and pass forwardly around the outside of the fire box to reach the combustion chamber and the fire tubes.

6. The arrangement of a plurality of rows 40 of staggered holes in each longitudinal member of the mud ring whereby a pair of parallel rows of contiguous water tubes may be provided in conjunction with each longitudinal member.

45 7. The use of flexible supports for the mud ring so that expansion of the boiler, the rear end of which is supported by the mud ring, is provided for.

50 8. The supporting of the grate carriers directly from the mud ring.

9. The arrangement of the mud ring so that substantially all sections are cylindrical to eliminate stays and stay bolts.

10. A novel form of reinforcing at the junction of the longitudinal members and 55 the intermediate cross member of the mud ring.

Other and further features of novelty not enumerated above will be more apparent to those skilled in the art from a consideration of the accompanying drawings and following specification wherein is disclosed a single exemplary embodiment of the invention it being understood, however, that such changes may be made therein as fall within 65 the scope of the appended claims without departing from the spirit of the invention.

In said drawings:

Fig. 1 is a side elevation of the boiler and fire box of a locomotive showing a portion 70 of the frame to illustrate the manner of supporting the fire box, the lagging and outer casing of the boiler and fire box being removed;

Fig. 1^a is a section thru connection 44 of 75 fig. 1.

Fig. 2 is a radial section on line 2—2 of Fig. 6;

Fig. 3 is a horizontal section through the 80 fire box on line 3—3 of Fig. 1;

Fig. 4 is a vertical section through the fire box taken on broken line 4—4 of Fig. 3;

Fig. 5 is a transverse vertical section taken on line 5—5 of Fig. 4;

Fig. 6 is a transverse vertical section taken 85 on broken line 6—6 of Fig. 1;

Fig. 7 is a fragmentary plan view of a portion of the mud ring partly in section on line 7—7 on Fig. 1;

Fig. 8 is a transverse section of the intermediate member of the mud ring taken on line 8—8 of Fig. 7 and showing the center grate bearer in position;

Fig. 9 is a section through the intermediate member of the mud ring taken on line 9—9 of Fig. 3 and showing a side grate bearer in position;

Fig. 10 is a fragmentary horizontal section of a longitudinal member of the mud ring taken on line 10—10 of Fig. 1 and 100

showing a center grate bearer support in position;

Fig. 11 is a transverse vertical section taken on line 11—11 of Fig. 10;

5 Fig. 12 is a section taken through the rear member of the mud ring on line 12—12 of Fig. 3 showing the rear support for the center grate bearer; and

10 Fig. 13 is a view similar to Fig. 12 taken on line 13—13 of Fig. 3 and showing the rear support for a side grate bearer.

Non-articulated steam locomotives for both passenger and freight service have about reached a maximum size. Their 15 height is limited by existing tunnel and bridge clearances; their width by track gauge and side clearances in tunnels and between tracks; their length by existing curves and other considerations, and their weight 20 by the number of supporting wheels which can be crowded into their length since the total load must be distributed as equally as possible over the track, the present capacity of which is just about equal to supporting 25 with safety the present locomotive. To increase the power of a locomotive some means must be provided which does not require a further increase in size. The use of higher steam pressures with a greater expansion 30 ratio offers a solution. With higher steam pressures, smaller cylinders can be used for the same or greater power, with a consequent reduction in the quantity of water which must be evaporated per unit of power. 35 Since less water is necessary per unit of power, the total boiler size can be less and the capacity for transferring heat from the fuel to the water can be increased. The present invention contemplates the provision 40 of a boiler which will be eminently satisfactory for operation with steam pressures of around 450 pounds to the square inch.

The added capacity for transferring heat from the fuel to the water is obtained, not 45 by increasing the number and length of the fire tubes, but by adding a plurality of water tubes which substantially surround and form the fire box and flame passages from the fire box to the combustion chamber and 50 the fire tubes. The flame passages are increased in length so that more heat can be extricated from the fuel and greater economy of operation effected.

Referring to the drawings it will be seen 55 from Fig. 1 that the boiler and fire box construction are shown by way of example to be mounted upon a substantially conventional locomotive frame 15 supported by the wheels 16. The usual barrel 17 is substantially circular in cross section and is closed 60 at the front end by the flue sheet 18 and at the rear end by the rear flue sheet 19. Between these flue sheets are arranged the usual fire tubes 20 in such quantities as to 65 substantially eliminate the use of stays.

The forward end of the barrel is supported in any conventional manner from the locomotive frame 15 as for instance from the steam cylinder and saddle assembly 15' as shown in Figure 1. The rear end is attached to and supported by the foundation ring or mud ring 21 forming a portion of the fire box construction. Extending rearwardly from the top at the rear end of the barrel 17 and having communication with the interior thereof are the two water drums 22 and 22' which extend to the rear end of the fire box. Extending above and centrally of the two water drums is the steam drum 23 whose rear end terminates somewhat forwardly of the rear ends of the water drums and whose front end extends over the major portion of the barrel and ends at the throttle chamber 23' which houses any desired form of throttle valve. From this throttle chamber extend the conduit 24 to the superheaters, not shown, or directly to the cylinders as desired.

The mud ring 21 comprises a one piece casting composed of the longitudinal tapering tubular members 25 connected together at their rear ends by the rear tubular member 26 and an intermediate tubular member 27 extending between the longitudinal members. At the front end, best shown in Figs. 1 and 6, the longitudinal members are bent inwardly toward the barrel and connected together mechanically by the large saddle flange 28 which is adapted to be securely riveted and fastened in a steam tight manner to the barrel as best shown in Fig. 6. The longitudinal members have their in-turned ends 31 in communication with the interior of the barrel through the openings 29 and the large cut-out portion 30 of the barrel. Between the elbow portions 31 of the longitudinal members is arranged the mud collecting cylinder 32 having communication, through the openings 33, with the interior of the barrel and having provision at 34 for the attachment of a blow-off cock. In plan, the mud ring is substantially rectangular having the intermediate connecting member between the longitudinal sides. This intermediate connecting member and the rear member are hollow as are the side members and all the parts are connected together to allow a free circulation of water from the barrel into all parts of the mud ring. At each corner, an inspection opening 35, closed by a suitable plug, is provided for assistance in inspecting and cleaning the ring. Likewise opposite the ends of the intermediate member are provided the openings 36 closed by plugs.

The upper surfaces of the longitudinal members of the mud rings are arranged substantially parallel to the corresponding undersurfaces of the water drums 22. The undersurfaces of the longitudinal members of

the mud ring slope upwardly toward the rear and gradually restrict the water passages from the barrel to the rear of the mud ring to prevent water-hammer. The slope is all provided in the lower surfaces in order that the distance between the upper surfaces and the water drums shall be equal at all positions throughout the length of the drums in order that the connecting water tubes 37 may be of the same length throughout and thus simpler and cheaper to construct. At the junction of the intermediate cross members 27 with the longitudinal members 25 of the mud ring, reinforcing flanges 38 are provided as shown in Fig. 7 to strengthen the longitudinal members and make up for the metal removed to allow communication between the longitudinal and transverse members. All sections of the mud ring are substantially cylindrical and hence no stay ing is necessary.

The water drums 22 and 22' are spaced apart as best shown in Fig. 5 and at their junction with the barrel and the rear flue sheet 19 they are reduced in size and shaped to an elliptical configuration as shown in Fig. 6. The barrel is provided with bumped-out portions 39 to receive these drums. The bumped-out portions extend rearwardly of the rear edge 40 of the barrel as shown at 41 in order that they may have a firm attachment to the water drums. As best shown in Figs. 2 and 6, the restricting of the water drums to form their elliptical ends takes place entirely on that portion of the drums within the general configuration of the barrel. This forms barriers 42 which assist in maintaining the water level in the water drums which take the place of the usual crown sheet in the conventional form of locomotive fire box and insure against these drums becoming dry, where exposed to the heat of the fire, such as on down grades. The normal level of water is shown in Fig. 6 and is near the horizontal center line of the said water drums.

The circulation of water in the boiler may be briefly stated as from the barrel into the mud ring, upwardly through the tubes 37, into the water drums, and thence back to the barrel. The water drums near their center are connected by pipes 43 to the steam drum 23 as shown in Figs. 1 and 5. The circulation of water is extremely rapid and in order to prevent the entrainment of water leaving the drums by the steam entering the steam drum, substantial continuations of the water drums 22 and 22' the steam drum and are provided by means

of the curved plates 45, best shown in Figs. 2 and 6. They form a barrier to keep the water which rushes from the water drums into the barrel from spreading until it is well past the steam inlet 44 so that water discharged from the drums into the barrel will not block the outlet therefrom into the steam drum.

The fire box is substantially defined and formed by water tubes connecting the longitudinal legs 25 of the mud ring to the two water drums. The upper surfaces of the longitudinal legs 25 of the mud ring are provided with four rows of openings suitably bossed for the reception of water tubes. These longitudinal rows of openings have their holes alternately staggered, i. e. the holes of the first and third rows are in the same transverse alignment as are the holes of the second and fourth rows. This provides for four sets of water tubes which may extend from each leg. As viewed in Fig. 5 these sets may be designated starting from the outside as A, B, C, and D. The pipes of the outermost set A extend substantially vertically from the legs 25 and then curve inwardly to meet the water drum closest thereto somewhat below the horizontal center line of this drum. It will be understood that the tubes are expanded in a suitable manner in each opening in the mud ring and the drum to form water-tight and steam-tight connections. Here it may be mentioned that the water drums are large enough for a man to crawl within and their rear closure members are removable and convertible. This constitutes the only manholes in the boiler and through them access may be had to the interior of the barrel.

The second row of tubes B first extend slightly outwardly until they reach the drums becoming dry, where exposed to the plane of the tubes A which they follow and heat of the fire, such as on down grades. The normal level of water is shown in Fig. 6 and is near the horizontal center line of the said water drums. Those through which the tubes A enter the boiler. It will be seen that the tubes are tapered at their ends and reduced in diameter so that the intermediate portions of the sets A and B can be contiguous, as best shown in Fig. 3, thus forming a solid wall of tubes between the points 47 and 48. The drum 23 as shown in Figs. 1 and 5. The staggering of the rows of tubes A and B around their entrance holes and thus the single connection between the barrel and the steam drum is by means of the casting 44 which makes its entrance into the barrel just forward of its rear end and just between the junctions of the water drums with the barrel. The circulation of water is extremely rapid and in order to prevent the entrainment of water leaving the drums by the steam entering the steam drum, sub-

The row of tubes C makes almost a flat surface, inclined inwardly between the mud ring and the bottom wall of the water drum on the same side of the fire box. The row of tubes D follows the row C as far as possible to form with it a solid wall of contiguous tubes, best shown in Fig. 3 and then extend past the junction of the barrel and the steam drum and are provided by means

D from opposite sides of the mud ring are interlaced at 51 at the top of the fire box and over this interlacing are laid the fire brick 52 to form the upper wall of the fire box. Suitable refractory material is arranged at 53, 54 and 55 between the tubes so that the fire box is outlined by two walls formed of sets of tubes C and D which converge and by the fire brick 55 and 52 and portions of the surfaces of drums 22 and 22' which are exposed to the fire between the tubes. Outside of the combustion chamber there is a passage P on each side which is defined by the wall of tubes C and D on its inner surface and the wall of tubes A and B on its outer surface assisted by the fire brick 53, 54 and 55.

The wall of tubes C D does not extend to the rear of the fire box, as seen in Fig. 3, whereas the wall of tubes A B extends from the rear to a substantial distance beyond the front of the fire box and partly outlines the combustion chamber space 56. Converging walls of fire brick 57 join the walls of tubes A B with the rear end of barrel, as shown in Figs. 3 and 4. As is customary, the fire box is covered with refractory lagging and a metal casing which may be seen in outline in Figs. 3, 4 and 5. This refractory material and metal casing may extend over the boiler and steam drum.

The rear wall of the fire box is composed of refractory brick 58 held in position by the water tubes 59 extending vertically upwardly from the rear member 26 of the mud ring and curved to meet the water drums.

A front wall of the fire box, which forms a complete barrier between the fire box and the combustion space 56, is formed of refractory brick 60 resting on the top surface of the intermediate member 27 of the mud ring and retained between a series of curved tubes 61 and 62, best seen in Figs. 3, 4 and 5. The top of the combustion chamber space between the water drums is formed by the refractory brick 63 supported by the tubes 64 arranged horizontally or in any manner preferred between the water drums 22 and 22', as shown in Figs. 4 and 5.

The refractories 60 near the bottom thereof may be provided with vertical flues 66 having communicating passages 67 leading into the fire box above the normal fuel level to supply extra air for the complete combustion of gases from the fire. This air may enter through passages 68 in the throat closure refractories 69.

From the construction just described, it will be seen that the gases and flames of combustion are formed in a fire box chamber closed at the front and top by water tubes which are heated by these flames. The flames must pass to the rear of the fire box where they heat the tubes 59 on the rear

wall and then must divide and completely reverse their direction and move forwardly between the rows of tubes A B and C D in the passages P thus heating on the outside of the rows of tubes C D, which they have previously heated on the inside. Completing the passage between the two rows of tubes, the divided portions of the flames reunite in the combustion chamber 56 where they heat the tubes 62 and then pass through the fire tubes 20 in the usual manner. The draft is, of course, induced by an exhaust nozzle when running and by a blower when standing in the conventional manner. The majority of the air for the combustion enters through the grates and auxiliary air through the passages 66, 67 and 68.

It has already been pointed out that the rear end of the barrel is attached to and supported by the mud ring. The whole weight of this portion of the barrel, of the mud ring, the water tubes, the water drums, and all of the fire box, is supported from the frame by means of flexible supports and sliding bearings. The flexible supports comprise the resilient vertical plates 70 and 71 which are attached to depending integral lugs 72 and 73. One of said lugs is integral with the rear transverse mud ring member 26 and the other with the saddle flange 28 at the forward end of the mud ring. These flexible plates are attached to the frame 15 in any suitable manner, not shown. Intermediate the ends of the longitudinal members 25 of the mud ring are arranged the integral depending webs 74 to which are attached the T-shaped sliding members 75 which cooperate with slide ways 76 secured to the frame. These intermediate slide guides support the main portion of the weight and the flexible members take their share and allow for movement of the mud ring to take care of the expansion and contraction in the whole boiler assembly due to temperature and pressure changes.

In order that the water tubes may be expanded into their respective openings in the mud ring, the bottom surface of this ring is provided with a plurality of openings. Preferably one opening of elliptical form is arranged beneath each four tube openings in the longitudinal members and corresponding arrangements may be provided in the other members. Suitable closure means will be provided for closing these openings.

The grate for use in conjunction with the fire box just described may comprise any conventional form of grate bars such as the shaking type shown at 77 and provided with depending shaker arms 78. However, the manner of supporting the grate bars is believed to be novel. The whole grate bar assembly is carried directly by the mud ring. Referring to Fig. 3 it will be seen

that the grate bars 77 each extend substantially half way across the mud ring, being supported at the outer ends by the side bearers 79 and at the inner ends by the center bearer 80. The side bearers comprise substantially flat metal straps standing on edge and supported front and rear in pockets formed of lugs cast integral with the mud ring. In Fig. 9 the forward end 5 of the side bearer 79 is shown slightly depending and received in the pocket in the lug 81 integral with the intermediate cross member 27. The pocket is such as to prevent lateral movement of the bearer and its end abutting against the intermediate member 10 prevents longitudinal movement. The rear end of the side bearer disclosed in Fig. 13 has its depending end resting in the pocket in the lug 82 formed integral with the rear transverse member 26 of the mud ring. The side bearers are kept out of 15 direct contact with the longitudinal members of the mud ring by stand-off flanges 92 shown in Figs. 5 and 11.

20 The center bearer at its front end is reduced in width at its lower portion and this reduced part rests between the lugs 83 projecting rearwardly from the intermediate member 27 of the mud ring, as shown in Figs. 3, 7 and 8. The broad portion of the center bearer 80 rests on top of these lugs as best seen in Fig. 8. The rear end of the center bearer is shown as forked in the present embodiment in order to accommodate 25 a typical stoking apparatus although this arrangement is not essential. The forked ends are mounted in exactly the same manner as the forward end between lugs 84 as best shown in Figs. 3 and 12.

30 The center bearer is made in three parts of deep truss section as shown in Fig. 3, which have stepped tongue and groove connections. In order to support the junction points of the three parts of the center 35 bearer, a pair of center bearer supports 85 are resorted to. These comprise transverse truss-like parts shown in elevation in Fig. 5 and having vertical central studs 86 adapted to be received in the hollows 87 in the enlarged ends of the center bearer sections to retain the same in position. These center bearer supports have their ends hung 40 in pockets 88 in the longitudinal members 25 of the mud ring as best shown in Figs. 5 and 11.

45 The grate bars have their reduced outer ends received in holes 90 through the side bearers 79 and their reduced inner end received in notches 91 in the center bearers.

50 From the above description, the novel features of the invention will be clearly evident. It will be seen that the design is extremely simplified, that the mud ring is a unitary casting providing means for its own support, 55 for the support of all the grate mechanism,

for the support of the rear end of the barrel, and for the reception of all of the water tubes and all of the refractory bricks. In operation, it will be found that the major portion of the steaming is done in the water tubes and that the fire tubes act to a large extent as water heaters. Since the greatest quantity of heat is exchanged when the difference in temperatures of two bodies is at a maximum, it will be seen that a greater quantity of heat can be taken up by the 70 cooler water in the barrel and thus the gas and flame temperature is reduced to a minimum before passing up the stack and being wasted. The steam drum, being entirely above and more or less isolated from the boiler, is less subject to water which may be splashed owing to rapid circulation of the water and to irregularities in the road bed so that there is almost no entrainment of moisture with the steam. The large steam 75 drum gives a large steam capacity for sudden demands. The boiler is substantially stayless in every respect and is not provided with manholes which weaken the construction of the barrel. The water tubes forming the fire box and the surrounding flame passages are given a maximum exposure to the heat and hence can extract a large quantity of heat from the flames before they enter the fire tubes.

Having thus described the invention, what is claimed as new and desired to be secured by Letters Patent is:

1. In a locomotive type boiler, in combination, a barrel having fire tubes therein, a fire box, a water drum communicating with and extending from said barrel over said fire box, a steam drum extending over said water drum and over substantially the full length of the barrel, a connection between the steam drum and barrel and a throttle valve chamber closing the forward end of said steam drum.

2. In a locomotive type boiler, in combination, a barrel having fire tubes therein, a fire box, a water drum communicating with and extending from said barrel over said fire box, a steam drum extending over said water drum and barrel and in communication with both the water drum and barrel to take steam therefrom and a steam outlet from said steam drum remote from its connection to said barrel.

3. In a locomotive type boiler, in combination, a barrel having fire tubes therein, a fire box, a water drum communicating with and extending from said barrel over said fire box, a steam drum extending over said water drum and barrel, there being a communicating passage between said steam drum and said barrel near the junction of said barrel water drum and means to direct water passing from said water drum into said barrel away from said passage and means

- to remove steam from said steam drum remote from said passage.
4. In a locomotive type boiler, in combination, a barrel having fire tubes therein, a fire box, a water drum communicating with and extending from said barrel over said fire box, a steam drum extending over said water drum and barrel, there being a communicating passage between said steam drum and said barrel near the junction of said barrel and water drum, said water drum having a continuation extending within said barrel beyond said passage and a steam outlet from said steam drum remote from said passage.
5. In a locomotive type boiler, in combination, a barrel having fire tubes therein, a substantially flat rear tube sheet for said tubes, a fire box of the water tube type, a pair of spaced water drums communicating with and extending rearwardly from the upper part of said barrel and tube sheet, substantially transverse tubes connecting said drums, refractory material supported by said tubes, said drums, tubes and refractory material forming the upper wall of a combustion chamber between the fire box and tube sheet, a substantially vertical wall between said combustion chamber and said fire box extending into gas tight engagement with said upper wall and flame passages only from the rear of the fire box to the combustion chamber.
6. In a locomotive type boiler, in combination, a barrel having fire tubes therein, a rear tube sheet, a fire box having completely closed sides and top, a combustion chamber between said fire box and tube sheet, a substantially vertical wall closing the front end of the fire box and completely separating it from the rear of the combustion chamber, and a flame passage below the level of the top of and completely isolated from all but the rear end of the fire box to connect it to the combustion chamber.
7. In a locomotive type boiler, in combination, a barrel having fire tubes therein, a pair of water drums extending from one end of said barrel and in communication therewith, a mud ring extending from said barrel below said drums and having spaced longitudinal members in communication with said barrel, water tubes connecting each longitudinal member with both drums, said tubes forming the closed side walls of a fire box and defining flame passages outside of said fire box and forming the sole passages from the rear of the fire box to the said fire tubes.
8. In a locomotive type boiler, in combination a barrel having fire tubes therein, a pair of laterally spaced water drums extending from one end of said barrel and in communication therewith, a mud ring extending from said barrel below said drums and hav-
- ing spaced longitudinal members in communication with said barrel, two sets of water tubes extending divergently from each longitudinal member, the outer set being connected to the near drum and forming a flame passage wall and the inner set having alternate tubes connected to the near drum and the remaining tubes to the far drum after passing close to the near drum, said inner set of tubes forming a substantially closed fire box wall.
9. In a locomotive type boiler, in combination, a barrel having fire tubes therein, a pair of laterally spaced water drums extending from one end of said barrel and in communication therewith, a mud ring extending from said barrel below said drums and having spaced longitudinal members in communication with said barrel, two sets of water tubes extending divergently from each longitudinal member, the outer set being connected to the near drum and forming a flame passage wall and the inner set having alternate tubes connected to the near drum and the remaining tubes to the far drum after passing close to the near drum, said inner sets of tubes and the parts of said drums only between the tubes of the inner rows forming a fire box.
10. In a locomotive type boiler, in combination, a barrel having fire tubes therein, a pair of spaced water drums extending from one end of said barrel near the top thereof and in communication therewith, a mud ring having a pair of spaced longitudinal members extending from said barrel near the bottom thereof and in communication therewith, a rear member and an intermediate member connecting said longitudinal members, two sets of water tubes extending divergently from each longitudinal member, the outer sets extending for substantially the full length of said members, said outer sets being connected to the near drums and forming flame passage walls, the inner sets extending from the junction of said intermediate member to near said rear member, the tubes of these sets forming fire box side walls and being alternately connected to the two drums to produce an interlaced top wall, tubes connecting said rear member and said drums to form a rear wall for said fire box, and means carried by said intermediate member to close the front end of said fire box.
11. In a locomotive type boiler, in combination, a barrel having a rear tube sheet and fire-tubes therein, a pair of spaced water drums extending from the barrel and tube sheet near the top thereof, a mud ring having a pair of spaced longitudinal members extending from said barrel near the bottom thereof, an intermediate water circulating member connecting said longitudinal members at a distance from said tube sheet, a

fire box beyond said intermediate member, a substantially vertical closure for the end of said fire box carried by said intermediate member and extending up to said water drums, the space between said flue sheet and closure constituting a combustion chamber, water tubes connecting said drums above said combustion chamber, refractory material supported by said tubes, said refractory material extending from said closure to said tube sheet and forming with said drums the top wall of said combustion chamber, a group of water tubes closing the full length of the top of said fire box below said drums and means defining a passage from the rear of the fire box to the combustion chamber.

12. In a locomotive, in combination, a frame, a boiler barrel supported at its front end by said frame, a foundation ring flexibly supported from said frame, the rear end of said barrel being carried solely by said ring.

13. In a locomotive, in combination, a frame, a boiler barrel supported at its front end by said frame, a foundation ring extending rearwardly from said barrel and supported by said frame, and a saddle on said ring supporting the rear end of said barrel and affording a water passage between said ring and barrel.

14. In a locomotive, in combination, a frame, a boiler barrel supported at its front end by said frame, a foundation ring extending rearwardly from said barrel and supported by said frame for longitudinal movement only thereon, and a saddle on said ring supporting the rear end of said barrel and grate structure wholly supported by said ring.

15. In a locomotive, in combination, a frame, a boiler barrel supported at its front end by said frame, a foundation ring extending rearwardly from said barrel, means supporting said ring from said frame for longitudinal movement in respect thereto, a saddle on said ring in which the rear end of said barrel is secured to support the same and water passages through said saddle to afford communication between the barrel and ring.

16. In a locomotive, in combination, a boiler barrel supported at the front end, a foundation ring comprising an integral casting including longitudinal tubular members of increasing sectional areas from rear to front, a rear connecting member and a boiler barrel supporting saddle, said saddle forming the sole support for the rear end of the boiler barrel.

17. In a foundation ring for a locomotive type boiler, an integral casting including longitudinal tubular members, a rear tubular member connecting said longitudinal members, inturned elbows on said longitudi-

nal members and a saddle flange connecting said elbows.

18. In a foundation ring for boilers, in combination, a tubular member of substantially circular cross section, a second tubular member of lesser diameter joining said first member intermediate its ends and supporting a load, supports for said long member remote from the junction, the hollows of the two members being in communication, and webs in the first mentioned member extending at an angle from the walls of the second member to strengthen the first member to make up for the material removed to admit the second member.

19. In a boiler of the locomotive type, in combination, a barrel, a water drum extending from said barrel, a mud ring member extending directly from said barrel, tubes connecting said drum and mud ring member, said member decreasing in cross section from said barrel outwardly to prevent water-hammer, the top of said member being parallel to said drum whereby said tubes can be formed in multiples.

20. In a boiler of the locomotive type, in combination, a barrel, a water drum extending from said barrel, a mud ring member extending directly from said barrel and adapted to take water therefrom, the upper surface of said member being parallel to said drum whereby a plurality of water tubes of the same length may be interposed between the drum and member, said member having its under surface converging toward the upper in a direction away from said barrel to prevent water-hammer.

In testimony whereof I hereunto affix my signature.

WILLIAM F. KIESEL, JR.
